Primary Examiner — Cynthia Underwood*(74) Attorney, Agent, or Firm* — Collard & Roe, P.C.(57) **CLAIM**

The ornamental design for a tablet cover, as shown and described.

DESCRIPTION

FIG. 1 shows an exterior front, side and bottom perspective view of a tablet cover showing my new design in a closed position with a tablet inserted;

FIG. 2 is an exterior front and rear view thereof in an open position;

FIG. 3 is an interior front and rear view thereof in an open position;

FIG. 4 is a bottom view thereof in a closed position, with the top view being a mirror image thereof;

FIG. 5 is an interior front, interior rear and bottom perspective view thereof in an open position with a tablet inserted; and, FIG. 6 is a bottom, interior rear and exterior front perspective view thereof in a raised position with a tablet inserted.

The features shown in broken lines show environmental structure only and form no part of the claimed design.
